Application February 13, 1943, Serial No. 475,746

12 Claims. (Cl. 240—10.67)

The invention relates to flashlights and has reference to a three-cell flashlight of improved construction wherein the reflector is advantageously arranged with respect to the cells to make the best of the space available therefor.

An object of the invention is to provide a portable flashlight of sturdy construction, having relatively few parts, and which are arranged so as to form a compact article of small size considering the power and efficiency of the unit.

A further object is to provide a flashlight of a portable nature having improved switch structure which can be easily manipulated by the operator.

Another object is to provide a switch including a movable switch slide for controlling the electric circuit to the light source and which will incorporate a push button for temporary use, the button when depressed closing the circuit to the light source even though the switch slide may be located in "off" position.

A further object is to provide novel means for holding the movable switch slide against displacement in any of a plurality of positions.

Another object is to provide a two-part flashlight casing for containing a total of three battery cells in compact arrangement and wherein the casing may be readily separated for insertion or removal of the cells and may also be held in connected relation by the threaded retainer for the reflector.

Another object is to provide a three-cell portable flashlight which will have an over-all height substantially equal to that of two cells in superposed relation.

Another object resides in the provision of a portable flashlight which will have an upright vertical position when placed on a table or on a desk or similar supporting structure and in which position the reflector will be angularly disposed.

Another object is to provide a flashlight having an improved form of casing for containing a plurality of battery cells and wherein the casing is split longitudinally to provide two halves substantially identical in construction.

With these and other objects in view the invention may consist of certain novel features of construction and operation, as will be more fully described and particularly pointed out in the specification, drawings and claims appended hereto.

In the drawings which illustrate an embodiment of the device and wherein like reference characters are used to designate like parts—

Figure 1 is a vertical sectional view of the three-cell flashlight of the invention showing in detail the reflector, the light source and the lamp socket;

5 Figure 2 is a vertical sectional view taken substantially along line 2—2 of Figure 1 with the movable switch slide being shown in "off" position;

Figure 3 is a side elevational view of the flashlight of the invention illustrating the location of the movable switch slide on the exterior of the casing;

10 Figure 4 is a detail sectional view of the switch structure showing the movable switch slide in "on" position;

Figure 5 is a horizontal sectional view taken substantially along line 5—5 of Figure 2;

15 Figure 6 is a bottom view of the flashlight casing;

20 Figure 7 is a sectional view taken substantially on the longitudinal center line of the bottom closure member;

Figure 8 is a transverse sectional view taken substantially along line 8—8 of Figure 7;

25 Figure 9 is a sectional view showing in detail the base structure for the lamp socket;

Figure 10 is an elevational view illustrating the flashlight of the invention in connection with a two-part casing and wherein the same is split longitudinally;

30 Figure 11 is an elevational view similar to Figure 10 but showing the other half of the casing;

35 Figures 12 and 13 are rear elevational views showing the two halves of the present casing in separated relation;

Figure 14 is a transverse sectional view illustrating the manner of joining the two halves of the longitudinally split casing;

40 Figure 15 is a front elevational view looking into the reflector portion of the present casing with the two halves in connected relation;

Figure 16 is a sectional view showing in detail the manner of interlocking the bottom portions of the casing sections; and

45 Figure 17 is a sectional view taken substantially along line 17—17 of Figure 14.

The casing of the present flashlight, indicated in its entirety by numeral 10, Figures 1 to 9 inclusive, is formed of metal which can be stamped, die cast or machined, or a plastic that can be molded to the shape desired under heat and pressure. For the purpose of this description it is assumed that the casing is molded of a plastic or other insulating material. In actual practice,

should the casing be made of metal, the electrical parts, such as the bulb socket, switch and battery connections, will have to be insulated from their supports. In a horizontal plane below the reflector the casing has a shape similar to a figure eight with one or more battery cells being located in each cylindrical portion of the casing. As best shown in Figure 1, the casing accommodates a total of three battery cells 11, 12 and 13, arranged as shown. The space which would accommodate the fourth cell is occupied by the reflector 15, light source 16, and metal lamp socket 17. This portion of the casing is formed with an upwardly projecting circular part 18, threaded on its exterior as at 20, and which threads function to threadedly secure to said part the metal retainer 21. This circular retainer carries the glass lens 22 and the reflector 15 which is located thereby within the part 18 of the casing. The releasable spring clip 23 holds the reflector in position.

The light source 16 and metal socket 17 are centrally located with respect to opening 24 in the reflector and said elements are also centrally located with respect to the partition 25. The partition is integral with the casing 10 and is formed of insulating material. If made of metal, parts mounted on the partition must be insulated.

The partition substantially closes the reflector section comprising the part 18 from the battery section of the casing. A central opening 26, Figure 9, is formed in the partition and the lamp socket 17 is located by means of this opening in a manner to be presently described in detail. Other openings shown in Figure 2 are provided in partition 25 for the passage of certain electrical conductors which comprise the circuit from the battery terminals to the switch and from the switch to the light source.

The battery cell 11 is placed within the casing 10 in inverted position with its negative terminal in contact with the negative conductor 27. Said conductor comprises a metal strip bent to the shape as shown in Figure 1 and which is held in place on the partition 25 by means of resilient fingers struck from the metal of the strip and which have contact with the downwardly projecting boss 28. The upwardly directed end of conductor 27 is bent to form a resilient portion 30 which has contact with the center pin 31 of the lamp socket.

The positive terminal 32 of the cell 11 is in contact with the metal conductor 33 suitably secured to the bottom closure 34 of the casing 10. A similar conductor 35 is disposed on the side of the closure member opposite conductor 33 and the same is in direct contact with the negative terminal of the cell 12. The positive terminal 36 of the cell 12 contacts the negative terminal of the cell 13 since these two cells are in superposed relation. The positive terminal 37 of cell 13 is in contact with the positive conductor, indicated in its entirety by numeral 38, the same being releasably secured to the partition 25 and having location on the side of said partition toward the reflector. The releasable securing of the metal conductor 38 to the partition is effected by the projecting bosses 40 and the resilient fingers 41 which are struck from the metal of said conducting strip. The conductor 38, best shown in Figure 2, is provided with a laterally extending portion 42 which has a ninety degree bend so as to extend through an opening 43 formed in the partition 25 of the casing. As a result said bent portion of the conductor 38 is

located in the battery section of the casing for convenient contact with the elements of the movable switch. Said bent portion is provided with a depending contact member 44 which is angularly bent so that the terminal end of the contact portion has considerable resiliency.

The negative conductor 27 is described as having contact with the negative terminal of the battery 11. Since the positive conductor 38 is in contact with the positive terminal of the battery 13 the circuit to the light source is made through said conductors by means of an intermediately positioned switch, which may be actuated from the exterior of the casing so that the operator may control the current. The pin 31 is in contact with the center electrode of the light source 16 and accordingly said pin must be suitably insulated from the conductor 38 and from the metal lamp socket 17. The threaded shell 45 of the light source provides the other electrode and this shell is in electrical contact with the metal of the lamp socket, as shown by Figure 1.

The coil spring 46 is included in the electrical connections from the shell 45 of the light source 25 to the lamp socket but in addition to this function, the coil spring also yieldingly maintains the bulb of the light source in contact with the wire bail 47. The base of the lamp socket is in contact with a switch conductor 48 which likewise 30 comprises a strip of metal, the same having location at one end adjacent the switch structure and having its opposite end located under the lamp socket. The terminal portion under the lamp socket is indicated by numeral 50 and it will be observed that this terminal portion is insulated from conductor 38 by means of the insulating button 51. Said button is provided with a hub 52, Figure 9, which extends through a central opening in the base of the lamp socket 17. The metal conductor 38, or at least that portion of the same which extends over the opening 26 in the partition, see Figure 9, is provided with a circular opening 53 substantially concentric with the hub 52 on the insulating button 51. The reason for this opening is to prevent contact between the pin 31 and the said conductor 38 since contact at this point would close the circuit to the light source and the switch would be rendered ineffective.

The insulating disc 54 carries the pin 31 and by reason of the recess formed in said disc the pin has limited movement in a longitudinal direction. The disc 54 is suitably secured to the metal lamp socket 17 by means of screws 55, Figure 9, the said screws passing through the insulating button 51 and the terminal portion 50 of the conductor 48. As a result the parts are suitably held together to form a unitary assembly, it being understood that the metal lamp socket is thereby secured to the conductor 38 which supports the lamp socket and positions the same centrally of the opening 26 formed in the partition 25. Since the screws 55 have contact with the metal lamp socket 17, it is necessary to space the screws from the conductor 38. For this reason the portion of the conductor 38 extending over the opening 26, Figure 9, is relatively narrow in width, it being made so by recesses 56 formed in the side edges of the conductor. The screws 55 securely join the insulating button 51 and the insulating disc 54 to the lamp socket but in so doing the screws are not in electrical contact with the conductor 38 although said conductor is confined between the parts and func-

tions as the supporting member for the lamp socket assembly.

The terminal portion 50 of the switch conductor 48 extends laterally on the side of the partition adjacent the reflector until the portion is 5 bent at a ninety degree angle similar to conductor 38 so that the same may pass through an opening 57 formed in the partition. From said opening the conductor 48 extends downwardly 10 for association with the switch. Said downwardly extending portion comprises a vertically disposed strip 58 which is in direct contact with the casing 10, as shown in Figure 2, along a substantially flat portion 60 of the casing disposed between the circular portions which contain the 15 cylindrical battery cells. In Figure 3 this flat portion 60 is shown as extending in a vertical direction and as having location substantially centrally of the length of the casing. Whereas, the strip 58 is in direct contact with the flat portion 20 on the inside of the casing, the movable switch slide 61 is in contact with said portion on the exterior of the casing.

The switch slide is provided with a push button 62 and with a hook portion 63. The push button and the hook portion both extend through an elongated slot 64 in the flat portion 60 of the casing, the length of this slot determining the extent of movement of the switch slide 61. A contact strip 65 is releasably secured to the 25 switch slide 61 by means of the hook 63. Said contact strip is formed with a slot 66, Figure 4, through which the entire hook 63 can be passed. By moving the contact strip downwardly with respect to the slide, the hook 67 can be inserted 30 through an opening in the contact strip provided therefor and as a result of this securement to the bowed resilient section of the contact strip the same is releasably fixed to the slide and will have vertical movements along with said slide. The lower end of the contact strip 65 is provided with a detent 68 which is located in either one of the 35 openings 70, 71, formed in the strip 58 of the conductor 48. With the detent located in opening 70, as shown in Figure 2, the switch slide is releasably held in "off" position. This is indicated by the fact that the contact strip 65 is in spaced relation with respect to depending contact 44 of the positive conductor 38. In Figure 4 the switch slide is shown in "on" position. In this position the detent 68 is located in opening 71 and the contact strip 65 is in electrical engagement with the depending contact 44.

With the switch slide in "on" position, it will be observed that the electrical circuit to the light source is closed through the various conductors and the contact strip 65 of the switch. From the battery 13 the electric circuit includes the conductor 38, its laterally extending portion 42, contact 44, and the switch contact 65. From the switch contact the current flows to the vertical strip 58 which is in electrical engagement therewith. This vertical strip forms part of the switch conductor 48 which is in electrical engagement by means of its terminal portion 50 with the lamp socket 17. From the lamp socket the current flows to the shell 45 of the light source. The center electrode of the light source is in electrical engagement with the pin 31 which is insulated so that it has contact only with the negative conductor 27. This negative conductor in addition to closing the circuit to the negative terminal of the battery 11 also resiliently biases the pin toward the light source so as to resiliently maintain the pin in contact with the center elec-

trode of the lamp. The circuit to the light source therefore may be controlled by movement of the switch slide 61 and in either of its two positions the slide is held by means of the detent 68 so that inadvertent displacement of the slide is prevented.

With the slide in "off" position, as shown in Figure 2, the circuit to the light source can be momentarily closed by pressing the button 62. Pressure on the button in a downward direction will flex the upper portion of the contact strip 65 so that this end thereof will engage the depending contact 44. This engagement is sufficient to close the circuit to the light source and current will be supplied to said light source as long as pressure is maintained on button 62. However, just as soon as the operator releases the button the contact strip 65 will spring back into place, in which position its top end is separated from contact 44 and the circuit to the light source is therefore open.

The metal conductors 33 and 35 comprise resilient upwardly bowed portions formed on the opposite ends of the same metal strip, which strip is secured to the bottom closure 34 by applying heat and pressure to the upstanding boss 72, shown in Figure 7. The boss is thus peened over the metal of said strip. Since the conductors 33 and 35 are securely fixed to the closure member they are removed with the closure member and therefore this bottom end opening of the casing will be unobstructed when the closure is removed to permit free passage into and from the casing of the flashlight. The bottom closure member 34 is substantially elliptical in plan elevation, as clearly evident from Figure 6. A ledge 73 is provided around the periphery of the member and on the inside of said ledge there is located an upstanding flange 74. The external dimensions of said flange approximate the inside dimensions of the bottom opening of the casing. Thus, in applying the bottom closure member to the casing the flange 74 guides the member into place so that the ledge 73 will be in contact with the bottom edges of the casing walls.

On the inside surface of the member 34 spaced upstanding ribs 75 are provided which function as supporting means for the conductors 33 and 35, respectively. Said bottom member below the conductor 35 is additionally formed to provide pivot means for a metal carrying bale 76. The pivot ends 77 of the bale are located within the portion 78 formed on the bottom closure member for the purpose. When the bale is not in use it is substantially retained within the socket portion 79.

A passage 80 is provided substantially along the transverse center of the closure member, a part of which is open, with the remainder being closed. 60 This passage extends diametrically of the circular openings 81. The openings receive the retaining screws 82 by means of which the bottom closure member 34 is releasably held to the casing. Each screw extends through a metal sheath 83, Figure 2, suitably fixed to the closure member so as to form a part thereof. The sheaths help to direct the threaded end of the screws into the metal inserts 84 located in portions 85 suitably secured to the walls of the casing 10. With the bottom closure member in place the openings 81 in the same will be located in alignment with the metal inserts 84. It is therefore only necessary to insert the screws and rotate them until they are in tight threaded engagement with the metal 70 inserts. As a result thereof the member 34 will

be securely retained in position, the bottom end of the casing will be completely closed, and the metal conductors 33 and 35 will be properly located so as to contact the positive terminal of battery 11 and the negative terminal of battery 12, respectively. It is desirable to rotate the screws 82 until the slot in their heads is in alignment with the transverse passage 80. This position of the screws is shown in Figure 6. A wire lock can now be inserted through this passage and the two ends sealed. Opening 86 in the boss 87 formed in the casing immediately below the reflector may be used to seal the lens ring 21 so that it cannot be removed. The lock also seals the battery casing so that the batteries cannot be removed while the flashlight is in use.

It is desirable at times to attach the portable flashlight of the invention to a belt or pocket of the user since when so held the light can very often be directed at the point desired and at the same time the user will have both hands free. The flashlight of the invention is therefore provided with a resilient clip identified by numeral 88, Figure 2, which clip is suitably fixed to the flat portion 89 of the casing, having location directly opposite the flat portion 60 which accommodates the movable switch slide. The metal rivets 90 fixedly secure the upper end of the clip 88 to the casing and the lower free end is bent outwardly at 91 to facilitate use of the clip in attaching the lantern to a belt or the like.

The casing for the flashlight of the invention has been previously described as simulating a figure eight in a transverse plane substantially through the center of the device. This constructional form of the casing is shown in Figure 5, wherein 92 indicates one of the substantially cylindrical sections and 93 indicates the other section. These sections are joined by the flat portions 60 and 89 which extend longitudinally, one on each side of the casing and which are symmetrically located with respect to both the longitudinal and transverse center lines.

The cylindrical section 92 is substantially twice as high as the section 93 and the sections accordingly retain two battery cells and one battery cell, respectively. In cylindrical section 92 the two battery cells are in superposed relation and the positive conductor 38 conducts the current therefrom to the switch structure. In section 93 the battery cell is inverted so that the negative conductor 27 electrically connects the same with the light source through the center pin 31.

The construction of the casing 10 according to the invention lends itself to a positioning of the reflector and light source above the cylindrical section of shorter height, namely, 93. Thus, the space which would be occupied by the fourth cell in this flashlight is taken up by the reflector, light source and lamp socket. The partition 25 forms a base for the reflector supporting portion 8 and said partition effectively separates the reflector supporting portion from the interior of the casing. As shown in Figure 1, the said reflector supporting portion is angularly disposed, the same forming an acute angle of approximately sixty degrees with the longitudinal center line of the casing.

In the modification shown in Figures 10 to 17 inclusive the flashlight casing is split longitudinally, each half section of the casing having a bottom formed integral therewith. In Figure 10 the numeral 110 indicates the main half section of the casing since this section carries the switch

structure and partition to which is secured the lamp socket and conductors. The numeral 114 indicates the other half section of the casing which is shown in Figure 11. When the two parts 5 of the casing are assembled, as in Figures 14 and 15, a portable flashlight is provided containing three battery cells compactly arranged.

Referring to Figure 10, the half section 110 is adapted to contain the battery cells 111, 112 and 113 arranged as shown. The space which would 10 accommodate the fourth cell is occupied by the light source 116, and metal lamp socket 117. This reflector supporting portion of each casing is formed by an upwardly projecting circular 15 part 118 having threads on its exterior as at 120 so as to receive the retainer which is threaded thereto and by means of which the two sections 20 of the casing are held in assembled relation. The retainer is clearly shown in Figure 1 and it will be understood that in this modified form of the invention said retainer also carries the glass lens and reflector in a manner as previously described.

The light source 116 and lamp socket 117 are centrally located with respect to the opening 126 25 which is positioned centrally in the partition 125. The partition is integral with the section 110 and a portion thereof projects outwardly beyond this main half section of the casing, as clearly illustrated in Figure 12. The battery cell 111 is 30 inverted so that its negative terminal is in contact with the negative conductor 127, which is suitably fixed to the undersurface of the partition, having its upwardly directed end constructed to form a resilient portion 130 having contact 35 with the center pin 131. The positive terminal 132 of cell 111 is in contact with the metal conductor 133 suitably secured as at 135 to the integral bottom portion of this section of the casing. Since the metal conductor is centrally positioned with respect to the flashlight casing as a whole a portion of the same projects beyond the half section 110 in a manner similar to partition 125. The purpose of conductor 133 is to conduct the electric current from the inverted cell 111 40 to cell 112 which has its positive terminal 136 in contact with the negative of cell 113. From the positive terminal 137 of this latter cell the current is conducted to the lamp socket by the positive conductor 138 which extends through an opening 45 140 in the partition 125 for the purpose. The laterally extending portion 142 of this positive conductor passes through opening 142 and is provided with a depending contact portion 144, as shown in Figure 10, by means of which the switch mechanism closes and opens the electric circuit to the light source.

The switch mechanism in this modified form of the invention is exactly the same as that previously described. The switch slide 161, Figure 12, is provided with a push button 162 and said slide is suitably fixed to the contact strip 165 located on the inside of the casing. By vertical movement of said contact strip the switch conductor 148 is electrically connected to contact portion 144 which has the effect of closing the circuit from the negative conductor 127, through the light source to the positive conductor 138. The lower end of the contact strip 165 is provided with a suitable detent 168 whereby the switch slide is releasably held in "On" and "Off" positions. Of course, the circuit to the light source can also be momentarily closed by pressing the button 162. Details of the switch structure 75 including the operation of button 162 has been

particularly described in connection with Figures 1, 2 and 3.

In this modified form of the invention the casing below the reflector supporting portion in a transverse plane may be described as comprising two semi-circular portions connected by straight lines. The contour of the assembled casing below the reflector supporting portion is best shown in Figure 17. As previously explained, each half section has an integral bottom and for securely holding the sections in assembled relation the bottom of 110 is provided with a depending lip 173 adapted to have interfitting relation with the groove 174 provided in the bottom of the companion section 114. When the sections are assembled the lip is first fitted in the groove and then the threaded retaining ring is screwed on the circular part 118 providing the reflector supporting portion of the casing. As a result of the interlocking engagement which the sections have when assembled it is only necessary to thread the metal retainer in place on the reflector supporting portion and the two parts of the present casing are securely held, effectively preventing inadvertent separation thereof. Also when the casing sections are assembled it will be understood that the projecting part of partition 125, as shown in Figure 12, will fit within section 114. In fact, the section 114 is provided with a groove 175, Figure 11, which coincides with the angular contour of the partition and said groove therefore receives the partition 125 when the casing sections are in assembled relation.

In both forms of the invention the cell 11 or 111 is prevented from moving upwardly beyond a predetermined distance by the stop rib 176, see Figures 1 and 10. The rib is formed on the inside of the casing and extends vertically from the partition to the battery cell. If it were not for the rib, the said battery cell would have a tendency to move toward the conductor 127, particularly when the flashlight is turned upside down. Such movement of the cell would bend the negative conductor and seriously damage the same. The rib 176 determines the inserted position of the inverted battery cell and accordingly the cell is retained between said rib and the bottom conductor 33 or 133.

Another feature of the invention resides in the provision of a contact strip which will make the flashlight operative even though only two cells are employed. By means of the contact strip the three-cell flashlight can be used on two cells. The feature is applicable to both forms of the invention although the same is disclosed only in connection with the modified form. In Figure 11 the contact strip 177 is suitably fixed at 178 to the inside of section 114. The strip is positioned within the groove 179 provided therefor in the inside wall of the casing section. Since the strip 177 is resilient it has a tendency to bow outwardly, which position is clearly indicated in Figure 13. In this bowed position, assuming that the sections of the casing are assembled without the battery cell 111, the upper end of the contact strip will engage the negative conductor 127 and the lower end will engage conductor 133. Electrical connection is therefore made to the light source even though cell 111 is not in place. The flashlight therefore will operate on battery cells 112 and 113 only.

It will be understood that when all three cells are in place within the casing the contact strip 177 is automatically rendered inoperative since the cell 111 will bear against the contact strip,

forcing the same into groove 179. With the contact strip rendered inoperative the battery cell performs its intended function of closing the electric circuit between conductors 127 and 133 and of delivering its portion of the current and voltage supplied to the light source when the switch is closed.

What is claimed is:

1. In a portable flashlight, a casing adapted to contain a plurality of battery cells and having a reflector supporting portion disposed at an angle to the longitudinal center line of the casing, said casing including separable sections each having an integral bottom part and also having half of the reflector supporting portion integral therewith, said sections being separable on a plane substantially parallel to the longitudinal center line, a partition carried by one of the sections and adapted to fit within the other section when the sections are assembled, said partition providing a base for the reflector supporting portion and separating said portion from the remainder of the casing, and a lamp socket located substantially centrally within the reflector supporting portion and supported by said partition.
2. A portable flashlight as defined by claim 1, additionally including reciprocable switch mechanism located on the section carrying the partition.
3. In a portable flashlight, a casing adapted to contain a plurality of battery cells and having a reflector supporting portion disposed at an angle to the longitudinal center line of the casing, said casing including separable sections each having an integral bottom part and also having half of the reflector supporting portion integral therewith, said sections being separable on a plane substantially parallel to the longitudinal center line, a partition fixed to one of the sections and adapted to have location within the other section when the sections are assembled, said partition providing a base for the reflector supporting portion and separating said portion from the remainder of the casing, and a lamp socket located substantially centrally within the reflector supporting portion and supported by said partition, and a metal conductor fixedly secured to the inside of the bottom part of the particular section also having the partition fixed thereto, said metal conductor electrically connecting certain of the battery cells in the casing.
4. In a portable flashlight, a casing of substantially oval shape in transverse section for containing a plurality of battery cells, said casing having a reflector supporting portion located adjacent the top thereof and disposed at an angle to the longitudinal center line of the casing, said casing including separable sections each having an integral bottom part and also having half of the reflector supporting portion integral therewith, said sections being separable on a plane substantially parallel to the longitudinal center line, a partition fixed to one of the sections and having location within the other section when the sections are assembled, said partition providing a base for the reflector supporting portion and separating said portion from the remainder of the casing, a lamp socket located substantially centrally within the reflector supporting portion and supported by said partition, and means provided on the bottom part of each section adapted to have interfitting engagement when the sections are assembled.
5. In a portable flashlight, a casing of substantially oval shape in transverse section for con-

taining a plurality of battery cells, said casing having a reflector supporting portion located adjacent the top thereof and disposed at an angle to the longitudinal center line of the casing, said casing including separable sections each having an integral bottom part and also having half of the reflector supporting portion integral therewith, said sections being separable on a plane substantially parallel to the longitudinal center line, a partition fixed to one of the sections and having location within the other section when the sections are assembled, said partition providing a base for the reflector supporting portion and separating said portion from the remainder of the casing, means provided on the bottom part of each section adapted to have interfitting engagement when the sections are assembled, and said reflector supporting portion having a threaded exterior for receiving retaining means to securely hold the sections in assembled relation.

6. An electric lamp comprising a casing of oval shape in transverse section and including an integral top wall, a removable bottom wall, and cylindrical sections for receiving battery cells, said casing having a maximum internal width approximately equal to that of a single cell, a maximum internal breadth approximately equal to that of two cells and a height sufficient to accommodate a plurality of cells, a circular reflector supporting portion projecting outwardly from one corner of the casing, an integral partition provided by the casing and forming a base for said reflector supporting portion, said integral partition being located adjacent the top wall in one cylindrical section and dividing the casing into a cell compartment and a lamp compartment, a lamp socket within the reflector supporting portion and supported by the partition, and a conductor supported by said removable bottom wall and having contact with a battery cell in each of the cylindrical sections for electrically connecting the cells.

7. An electric lamp comprising a casing of oval shape in transverse section and including an integral top wall, a removable bottom wall and cylindrical sections for receiving battery cells, said casing having a maximum internal width substantially equal to that of a single cell, a maximum internal breadth substantially equal to that of two cells, and a height sufficient to accommodate a plurality of cells, a circular reflector supporting portion projecting outwardly from one corner of the casing at an angle to the longitudinal center line, an integral partition within the casing providing a base for the reflector supporting portion, said partition dividing the casing into a cell compartment and a lamp compartment, a lamp socket supported by the partition and located on the reflector side thereof, a switch conductor in the cell compartment having a portion extending through an opening in the partition and electrically connecting with the lamp socket, switch mechanism supported by the casing and having operative association with said switch conductor, and other conductors supported by said partition and having electrical contact with certain of said battery cells, said switch mechanism in operative position electrically connecting one of said other conductors with the switch conductor.

8. In a portable flashlight, a casing of substantially oval shape in transverse section and including longitudinal portions for retaining battery cells, said casing having a top wall and a bottom

wall, one longitudinal portion having a height greater than that of the other portion, the portion of greater height containing a plurality of battery cells whereas the portion of less height contains a less number of cells, a partition extending diagonally downward from the top wall in alignment with and above the portion of less height, said partition dividing the casing into a cell compartment and a lamp compartment, a reflector supporting portion extending outwardly from the partition, a lamp socket within the lamp compartment and supported by said partition, a conductor electrically connected to the lamp socket and extending through an opening in the partition into the cell compartment, and a member supported by said bottom wall and extending into said portions respectively for electrically connecting the battery cells in said portions.

9. In a portable flashlight, a casing of substantially oval shape in transverse section and including longitudinal portions for retaining battery cells, said casing having a top wall and a bottom wall, one longitudinal portion having a height greater than that of the other portion, the portion of greater height containing a plurality of battery cells whereas the portion of less height contains a less number of cells, a partition extending diagonally downward from the top wall in alignment with and above the portion of less height, said partition dividing the casing into a cell compartment and a lamp compartment, a reflector supporting portion extending outwardly from the partition, a lamp socket within the lamp compartment and supported by said partition, a conductor electrically connected to the lamp socket and extending through an opening in the partition into the cell compartment, and a member supported by said bottom wall and extending into said portions respectively for electrically connecting the battery cells in said portions.

10. In a portable flashlight, a casing of substantially oval shape in transverse section and including longitudinal portions for retaining battery cells, said casing having a top wall and a bottom wall, one longitudinal portion having a height greater than that of the other portion, the portion of greater height containing a plurality of battery cells whereas the portion of less height contains a less number of cells, a partition extending diagonally downward from the top wall in alignment with and above the portion of less height, said partition dividing the casing into a cell compartment and a lamp compartment, a reflector supporting portion extending outwardly from the partition, a lamp socket within the lamp compartment and supported by said partition, a conductor electrically connected to the lamp socket and extending through an opening in the partition into the cell compartment, and other conductors supported by the partition and having electrical contact with certain of said battery cells.

11. In a portable flashlight, a casing of substantially oval shape in transverse section and including two cylindrical sections for retaining battery cells with their axes disposed in spaced parallel relation, said casing having a top wall and a bottom wall and having a flat longitudinally extending portion between the cylindrical sections on each side of the casing, one of said cylindrical sections having a height greater than that of the other section, a partition fixed to the

70
75

casing and extending diagonally downward from the top wall in alignment with and above the cylindrical section of shorter height, a circular reflector supporting portion extending outwardly from the partition and forming a lamp compartment with said partition, a lamp socket within the lamp compartment and supported by said partition, switch mechanism positioned on one of said flat longitudinally extending portions and including a switch conductor, and said switch conductor having a portion extending through an opening in the partition and electrically connecting with the lamp socket.

12. In a portable flashlight, a casing of substantially oval shape in transverse section and including two cylindrical sections for retaining battery cells with their axes disposed in spaced parallel relation, said casing having a top wall and a bottom wall and having a flat longitudinally extending portion between the cylindrical 20

sections on each side of the casing, one of said cylindrical sections having a height greater than that of the other section, a partition fixed to the casing and extending diagonally downward from the top wall in alignment with and above the cylindrical section of shorter height, a circular reflector supporting portion extending outwardly from the partition and forming a lamp compartment with said partition, a lamp socket within the lamp compartment and supported by said partition, switch mechanism positioned on one of said flat longitudinally extending portions and including a switch conductor, other conductors fixed to said partition and adapted to electrically connect with certain of said battery cells, and a member carried by said bottom wall and extending into the sections respectively for electrically connecting the battery cells in said sections.
